UNITED STATES PATENT OFFICE.

JOSEPH MATHISON, OF BOSTON, MASSACHUSETTS, ASSIGNOR TO ROWEN-MATHISON MACHINERY COMPANY, A CORPORATION OF MAINE.

FEEDING DEVICE.

No. 902,827.

Specification of Letters Patent.

Patented Nov. 3, 1908.

Application filed March 12, 1908. Serial No. 420,656.

To all whom it may concern:

Be it known that I, JOSEPH MATHISON, a citizen of the United States, residing at Boston, in the county of Suffolk and State of Massachusetts, have invented new and useful Improvements in Feeding Devices, of which the following is a specification.

My invention relates to improvements in feeding devices in which buttons or the like are fed from a hopper to a raceway. In devices of this class now in use the hopper is so constructed that when the same is removed for the purpose of emptying the buttons or the like therefrom and replacing them by buttons of a different size or color, the buttons fall onto the floor while the hopper is being disconnected from its support.

The object of my invention is to provide a detachable closure for the lower opening 20 of the hopper which shall remain connected to the hopper when the same is being detached from its support, thereby preventing the escape of the buttons and which may be subsequently disconnected from said hopper 25 to allow the buttons to be removed therefrom.

The invention consists in the combination and arrangement of parts set forth in the following specification and particularly 30 pointed out in the appended claims.

Referring to the drawings: Figure 1 is a central vertical sectional elevation of a feeding device embodying my invention. Fig. 2 is a plan section taken on line A—A 35 of Fig. 1.

Like numerals refer to like parts throughout the several views of the drawings.

In the drawings, 5 is a support on which a hopper 6 is mounted, said hopper being secured to said support by means of screws 40 7, 7. The hopper 6 is provided with an inlet passage 8 through which the buttons may be introduced into said hopper, said hopper being also provided with an outlet 45 orifice 9 through which the buttons are adapted to pass outwardly into a raceway 10. The bottom of the hopper 6 is provided with an opening 11 in which is located a plate 11' which may be secured to an agi- 50 tator 12 comprising a hub 13 extending upwardly and outwardly through a hole 14 provided in the hopper 6, there being a plurality of brushes 15 mounted on said hub. The hub 13 is provided with a hole 16 in 55 which is located a shaft 17 detachably con-

nected to said hub by means of a thumb-screw 18 having screw-threaded engagement with said hub and bearing against said shaft. The shaft 17 extending downwardly from the agitator 12 passes through the support 60 5 and is journaled therein. An arm 19 fast to the lower end of the shaft 17 may be connected to any suitable mechanism to impart a rocking motion thereto, whereby the agitator 12 is rocked within the hopper 6 and 65 the buttons located in said hopper are caused to pass therefrom through the outlet orifice 9 into the raceway 10. A collar 20 which is fast to the shaft 17 by means of a set screw 21 prevents displacement of said shaft 70 when the hopper and agitator are removed as hereinafter described. A U-shaped guard 22 is secured within the hopper 6 adjacent to the inlet passage 8 and serves to prevent the agitator 12 from throwing any buttons 75 outwardly through said inlet passage.

When it is desired to remove the buttons in the hopper and replace them by buttons of a different size or color, the operator unscrews and removes the thumb-screw 18 and 80 the screws 7. He then grasps that portion of the hub 13 which projects above the hopper 6 and pulls upwardly thus causing the agitator 12 and plate 11' to slide upwardly in the hopper 6 until said plate strikes a 85 shoulder 23 formed in said hopper thus preventing the escape of buttons outwardly through the outlet orifice 9. Continued upward movement of the hub 13 results in the hopper 6 being separated from the support 5 90 and said hopper and the agitator 12 are thus removed bodily leaving the shaft 17 in its place on the support 5. The hopper 6 may now be held over a suitable receptacle for the buttons and the hub 13 is then released 95 from the fingers allowing the agitator 12 together with the plate 11' to be removed from the hopper, thereby allowing the buttons to drop into the receptacle which is provided for that purpose. The agitator 12 and 100 hopper 6 are then replaced on the shaft 17 after which the set screw 18 is screwed against said shaft and the screws 7 which were previously removed are then replaced and the hopper may be refilled with buttons. 105

While I have described the plate 11' and the agitator 12 as being removable for the purpose of removing the buttons from the hopper, said plate and agitator need not necessarily be removed to accomplish this, but 110

- it may be done in the following manner. After the screws have been removed the agitator 12 and plate 11' may be drawn upwardly transversely of the outlet orifice 9, thereby cutting off the escape of the buttons through said orifice and the hopper may then be removed from the machine and inverted, thereby allowing the buttons to pass outwardly from the inlet passage 8.
- 10 Having thus described my invention, what I claim and desire by Letters Patent to secure is:
1. In a feeding device, a hopper provided with an outlet orifice and having also an opening leading thereto, a raceway leading from said orifice, an agitator located within said hopper, a closure for said opening fast to said agitator, and a shaft to which said agitator is detachably attached.
  2. In a feeding device, a hopper provided with an outlet orifice and having also an opening leading thereto, a raceway leading from said orifice, an agitator rotatably mounted within said hopper and extending outwardly therefrom, a closure for said opening fast to said agitator, a shaft, and means located outside said hopper detachably connecting said agitator to said shaft.
  3. In a feeding device, a hopper provided with an outlet orifice and having also an opening leading thereto, a raceway leading from said orifice, an agitator rotatably mounted within said hopper and having a tubular stem extending outwardly therefrom, a closure for said opening fast to said agitator, a shaft located in said stem, and means for detachably connecting said agitator to said shaft.
  4. In a feeding device, a hopper provided with an outlet orifice and having also an opening leading thereto, a raceway leading from said orifice, a support for said hopper, and a closure for said opening interposed between said support and the interior of said hopper and detachably connected to said hopper.
  5. In a feeding device, a hopper provided with an outlet orifice and having also an opening leading thereto, a raceway leading from said orifice, an agitator located within said hopper, and a closure for said opening fast to said agitator.
  6. In a feeding device, a hopper provided with an outlet orifice and having also an opening leading thereto, a raceway leading from said orifice, an agitator rotatably mounted within said hopper, and a closure for said opening fast to said agitator.
  7. In a feeding device, a hopper provided with an outlet orifice and having also an opening leading thereto, a raceway leading from said orifice, an agitator rotatably mounted within said hopper and extending outwardly therefrom, a support for said hopper, and a closure for said opening fast

to said agitator and interposed between said support and the interior of said hopper.

8. In a feeding device, a hopper provided with an outlet orifice and having also an opening leading thereto, a raceway leading from said orifice, an agitator located within said hopper, a support for said hopper, a closure for said opening fast to said agitator and interposed between said support and the interior of said hopper, and a shaft journaled in said support and detachably connected to said agitator.

9. In a feeding device, a hopper provided with an outlet orifice and having also an opening in the bottom thereof, a raceway leading from said orifice, an agitator located within said hopper, a support for said hopper, and a closure for said opening detachably connected to said hopper.

10. In a feeding device, a hopper provided with an outlet orifice and having also an opening in the bottom thereof, a raceway leading from said orifice, an agitator located within said hopper, a support for said hopper, and a closure for said opening detachably connected to said hopper and interposed between said support and the interior of said hopper.

11. In a feeding device, a hopper provided with an outlet orifice and having also an opening in the bottom thereof, a raceway leading from said orifice, an agitator located within said hopper and having a hub extending outwardly through the upper side thereof, a closure for said hopper fast to said agitator, a shaft extending into said hub, and means for detachably connecting said shaft to said hub above said hopper.

12. In a device for feeding buttons or the like, a hopper provided with an outlet orifice and having also an opening leading thereto, a raceway leading from said orifice, and a closure for said opening adapted to be moved transversely of said outlet orifice, whereby the escape of buttons from said outlet orifice may be cut off.

13. In a device for feeding buttons or the like, a hopper provided with an outlet orifice and having also an opening leading thereto, a raceway leading from said orifice, and a closure for said opening adapted to be moved transversely of said outlet orifice, whereby the escape of buttons from said outlet orifice may be cut off, said closure being adapted to be subsequently moved into position to permit the escape of buttons from said opening.

14. In a device for feeding buttons or the like, a hopper provided with an outlet orifice and having also an opening leading thereto, a raceway leading from said orifice, and a closure for said opening adapted to be moved transversely of said outlet orifice, whereby the escape of buttons from said outlet orifice may be cut off, said closure being

adapted to be subsequently disconnected from said hopper to permit the escape of buttons through said opening.

15. In a device for feeding buttons or the like, a hopper provided with an outlet orifice and having also an opening leading thereto, a raceway leading from said orifice, an agitator located in said hopper, and a device connected to said agitator and adapted to 10 be moved thereby transversely of said outlet

orifice, whereby the escape of buttons from said outlet orifice may be cut off.

In testimony whereof I have hereunto set my hand in presence of two subscribing witnesses.

JOSEPH MATHISON.
